COLLAPSIBLE LAST

Alexander W. McNeill, Lynn, Mass.

Application April 4, 1951, Serial No. 219,216

8 Claims. (Cl. 12—136)

1

This invention comprises a new and improved last constructed and arranged to collapse freely, completely and quickly, and on that account being particularly useful in the manufacture of slip lasted shoes, and at the same time having novel connecting mechanism that is effective to hold the last in solid locked condition with an exceptional degree of firmness and security. Accordingly the last of my invention is also well adapted and useful in the manufacture of welt and cemented shoes where the last must be subjected to severe pressure in the sole laying operation or in other steps of the manufacturing process.

For many years shoemakers have sought for a last construction that would permit a quick and substantial collapse and shortening of the last in order that it may be withdrawn easily from the upper without undue strain, and which also will insure the lengthening of the last after it has been fully introduced into the upper. These characteristics are particularly important in the manufacture of slip lasted shoes having uppers of delicate material.

Another essential requirement is that the operations of locking and unlocking of the last must be effected practically instantaneously. For example, the time required to manipulate a threaded connection makes all such mechanism entirely unsuitable for modern shoemaking requirements. In accordance with the present invention these operations require no more time than is needed to break or straighten a toggle joint.

Still another requirement is that the last when in locked or expanded condition must have sufficient strength to withstand very heavy pressure without danger of breakage. It is important that the hinge pins should be so located that they will not split the wood of the last or pull out in resisting sole laying pressure or the like.

The last of the present invention possesses all these desirable characteristics and others that have been found extremely important by the shoemaking industry. Going more into detail, my improved last includes in its structure a tie link that reinforces the peak of the forepart against splitting and permits location of the anchor pins of the connecting mechanism in positions most favorable to the rapid collapsing movement of the last. On account of its tapering shape the peak of the forepart is the most delicate portion of the last and heretofore many lasts have been damaged by splitting under internal toggle pressure augmented by external sole lay-

2

ing pressure. Consequently the location of the anchor pins has been governed by the necessity of providing sufficient solid wood to withstand such pressure and such locations have not always favored a free and quick collapse of the last. Now, however, there is provided a positive metal connection between the upper and lower portions of the forepart where it is most effective to reinforce the peak of the forepart.

10 Another feature of my improved last is that the parting cut between the heel and forepart includes an initial cut at right angles to the last bottom creating a solid butt which preserves the bottom line of the last and obviates the danger 15 of splitting the bottom of the forepart. This is particularly important in those cases where the manufacturer employs an upper which is a half size under the last and so produces a lasted shoe which is excessively tight and which must be 20 pulled off the last with brutal force. Where the parting cut is at an angle, the forepart is likely to slip up slightly with a powerful wedging effect that splits off the bottom of the forepart under the instep. I have discovered that this weakness 25 may be obviated by making a right angle cut of $\frac{1}{16}$ " to $\frac{1}{8}$ " which leads into the usual angle cut. This right angle cut may be straight or it may be made on a 1" radius. With a last fashioned in this manner I find that a pressure of 30 2000 lbs. will be satisfactorily resisted without any misalignment of the parts.

Another feature of my improved last consists in a toggle plate of skeleton form of such shape as to permit a slight yield when the joint of the toggle passes the dead center. This permits the employment of stiffer and stronger tension links and a somewhat more favorable location of the anchor pins for the tension links so that more wood is left in the last bottom and there is 40 no danger of the pins pulling through.

These and other features of the invention will be best understood and appreciated from the following description of a preferred embodiment thereof, selected for purposes of illustration and 45 shown in the accompanying drawings in which:

Fig. 1 is a view in elevation of the last with portions broken away to expose the connecting mechanism.

Fig. 2 is a similar view showing the last in collapsed condition.

Fig. 3 is a cross-sectional view on the line 3—3 of Fig. 1.

Fig. 4 is a similar view on the line 4—4 of Fig. 1, and

Fig. 5 is a view of a modified linkage.

The last as herein shown comprises a heel part 10 and an interfitting forepart 11. The meeting faces of these parts are complementary to each other except that they diverge toward the cone of the last to provide an open space into which an operating portion of the connecting mechanism projects so that it may be manipulated in collapsing or straightening the last. The parting line includes a straight portion 12 disposed at right angles to the last bottom and providing a butt of solid wood. The heel part is provided with a slot 13 and the forepart with a corresponding slot 14, and in these registering slots the connecting mechanism is housed.

The connecting mechanism comprises a pair of elongated tension links 15 herein shown as curved and slotted, but not necessarily so. They are identical in shape and provided with an anchor pin 16 in the forepart and an anchor pin 17 in the heel part. These links are disposed in the lower portion of the last. They are themselves the subject matter of my prior Patent No. 2,188,414 dated January 30, 1940, although they are herein shown as employed in a new combination.

The tension links 15 are separated by an intermediate spacer or toggle plate 18 which is pivotally mounted upon the anchor pin 17 for the rear end of the tension links. The toggle plate 18 is connected by a pivot pin 19 to a pair of angular toggle links 20. At their forward ends the toggle links 20 are mounted upon an anchor pin 21 in the forepart of the last. The pin 19 constitutes the knuckle joint of the toggle system and this is broken slightly past the dead center position as indicated in Fig. 1 when the toggle is straightened and the last locked in extended position. As shown in Fig. 1, the tension links 15 yield slightly and permit full straightening of the toggle links in reaching their final locked position. The toggle links are locked in this position by engagement of the angular toggle links 20 with the upper edge of the tension links 15 as shown in Fig. 1. The toggle links 20 are herein shown as having parallel arms extending upwardly into the open space between the parts of the last and these are provided with eyes that may be engaged by a hook manipulated by the operator for convenience in breaking the toggle.

A substantially vertical tie link 22 extends between the anchor pins 16 and 21 and constitutes a positive metal connection between these areas in the forepart of the last. The tie link 22 lies in the same plane as the toggle plate 18 and between the pair of tension links 15 and the pair of angular toggle links 20. This link is a stationary element in the last construction and performs its function independently of the movement of the links of the connecting mechanism.

When the last is locked in its fully extended position as shown in Fig. 1, the tension links 15 hold the meeting surfaces of its two parts firmly in contact and in the proper alignment for the bottom line of the last. The toggle 18-20 exerts powerful separating pressure upon the anchor pins 17 and 21 so that the two parts of the last are held in operative position by the leverage pressure of the toggle in cooperation with the tension of the links 15. Meanwhile the tie link 22 prevents any separating movement between the anchor pins 16 and 21 which would otherwise be resisted only by the wood of the forepart. Heretofore in some cases the strength of the wood in this area has been in-

sufficient to prevent the peak of the forepart from splitting.

In Fig. 5 is shown a modified connecting linkage similar in many respects to that already described and within the scope of the present invention. In this linkage the toggle plate 23, instead of being solid as shown in Figs. 1 and 2, is skeletonized so as to permit a slight spring yield when the toggle 20-23 is straightened; that is, the distance between the anchor pin 17 and the pivot pin 19 is permitted to contract slightly as the toggle passes its dead center position. In this mechanism the tension links 15 are shown as reversed in position and in this combination these links are made somewhat heavier and stiffer than the links 15 illustrated in Figs. 1 and 2 because they are not required to yield in straightening the toggle, or if they yield their elongation is less than that required of the tension links 15 because of the yielding capacity of the skeletonized toggle plate 23.

In collapsing the last it is necessary only to insert a hook in the eye of the upwardly extending branches of the toggle links 20 and pull them forcibly upwardly, whereupon the meeting faces of the heel and foreparts permit rapid shortening and collapsing of the last as indicated in Fig. 2. The action of the connecting mechanism shown in Fig. 5 is similar in this respect to that illustrated in Figs. 1 and 2. It will be clear that the branch with the eye for the hook may be formed either as a part of the links 20 or the toggle plate 18. It will also be noted that the arrangement of tension links 15 shown in Fig. 1 permits the bottom of the last to be left solid with a substantial thickness of wood and without requiring the presence of a slot opening in the last bottom.

Having thus disclosed my invention and described in detail illustrative embodiments thereof, I claim as new and desire to secure by Letters Patent:

1. A collapsible last comprising interfitting heel and foreparts having registering slots, and connecting means located in said slots and including a flexible link having an anchor pin in each of said parts, toggle links also connecting said parts, anchor pins therefor, one of said pins passing through one end of said flexible link and the second pin being spaced a substantial distance from the other end of the said flexible link, and a tie link positively connecting the two anchor pins in the forepart of the last.

2. A collapsible last comprising interfitting heel and foreparts, a double tension link, anchor pins at the ends of the link in the respective last parts, a spacer plate located between the two members of the tension link and pivoted on the rear anchor pin of the link, a double toggle link pivotally connected to the spacer plate, an anchor pin therefore located in the forepart of the last, and a tie link connecting the latter anchor pin with the anchor pin at the forward end of the double tension link.

3. A collapsible last having interfitting heel and foreparts, a tension link connecting said parts near the last bottom, anchor pins for the link in the respective last parts, a toggle plate pivoted upon the rear anchor pin of the tension link, an angular toggle link pivoted on the toggle plate and having an upstanding operating arm whereby the toggle may be broken or straightened, an anchor pin in the forepart of the last for the said angular toggle link, and a tie link connect-

ing the latter anchor pin with the anchor pin at the forward end of the tension link.

4. A collapsible last comprising interfitting heel and foreparts, a curved and slotted tension link connecting the two parts in the lower portion of the last, a toggle plate curved at its lower edge in conformity to one edge contour of the tension link, a toggle link pivoted to the toggle plate and having a contact surface shaped to engage the other edge of the said link when the toggle as a whole is moved to its substantially straightened condition, and a link providing a positive tie between the forward ends of the tension link and the toggle link.

5. A collapsible last comprising complementary heel and foreparts, links connecting the said parts, and a vertical tie link disposed in the forepart and having a pin at each end thereby supporting the top of the forepart against splitting.

6. A last of the character described in claim 5

20

in which the two last parts are separated in part by a short cut at right angles to the bottom of the last.

7. A collapsible last comprising complementary heel and foreparts, a system of linkage connecting said parts and including toggle links, one of which is in skeleton form and can yield in passing the dead center position.

8. A collapsible last comprising heel and foreparts, a vertical tie link in the forepart tying together spaced areas therein, tension links disposed on both sides of the tie link connecting the two parts of the last, and toggle links also disposed on both sides of the tie link and constituting one member of a toggle system between the two parts of the last.
